UNITED STATES PATENT OFFICE.

ROBERT EMERSON BROWN, OF TIDIOUTE, PENNSYLVANIA.

RAZOR-STROP.

947,011.

Specification of Letters Patent. Patented Jan. 18, 1910.

Application filed February 23, 1909. Serial No. 479,362.

To all whom it may concern:

Be it known that I, ROBERT EMERSON BROWN, a citizen of the United States, and a resident of Tidioute, in the county of 5 Warren and State of Pennsylvania, have invented a new and Improved Razor-Strop, of which the following is a full, clear, and exact description.

The invention is an improvement in razor 10 strops, and has in view a simple and effective means to connect the strop with the swiveled suspending eye or device, avoiding the usual bolt and nut arrangement which is generally found objectionable for the reason that it wastes a substantial length of the 15 strop, is bad in appearance, scrapes and scratches wherever it contacts and is unsatisfactory in packing several strops together in a box.

20 My invention may in general be defined as consisting of a split tube, stropping members extending through the split portion of the tube, having an enlargement arranged within the tube and pinched at the outer 25 sides by the edges of the tube, and a device to suspend the strop, attached to the tube.

Reference is to had to the accompanying drawings forming a part of this specification, in which similar characters of reference 30 indicate corresponding parts in all the views.

Figure 1 is a face view of a razor strop constructed in accordance with my invention; Fig. 2 is a longitudinal section on the 35 line 2—2 of Fig. 1; and Fig. 3 is a perspective view of the split tube and suspending eye removed from the strop.

The invention essentially consists of a tube 5 and eye 6 swiveled in the tube near 40 the center, with the tube slotted or split longitudinally directly opposite the eye. The tube is preferably constructed of spring sheet metal and the eye is secured thereto

by upsetting or riveting over its inner end, as shown in Fig. 2. The leathers or members 45 7 and 8 of the strop are thinned to an edge at their inner ends and hooked or folded toward each other, with the edges stitched together as indicated at 9. This manner of connecting the leathers or members 50 of the strop forms an enlargement 10. The tube 5 is slid transversely of the stropping members over the enlargement 10, until the ends of the tube register with the opposite edges of the stropping member, as 55 shown in Fig. 1. With the tube in this position it is impossible to pull out the stropping members, not only by reason of the enlargement 10 but also by reason of the pinching of the stropping members together 60 by the edges of the tube. A suspending device thus constructed and applied to the stropping members, leaves very little of the length of the latter ineffective for stropping 65 purposes, and the strops may be closely packed for shipment.

Having thus described my invention, I claim as new and desire to secure by Letters Patent:

In a razor strop, a split spring tube, presenting a continuous curved and uninterrupted upper portion, stropping members extending through the split portion of the tube, having an enlargement arranged within the tube and pinched at the outer sides 70 75 by the edges of the tube, and a device to suspend the strop, swiveled in the upper portion of the tube.

In testimony whereof I have signed my name to this specification in the presence of 80 two subscribing witnesses.

ROBERT EMERSON BROWN.
